ELECTRIC FLATIRON

Filed Oct. 21, 1922

2 Sheets-Sheet 2

UNITED STATES PATENT OFFICE.

WILLIAM T. HOOFNAGLE, OF GLEN RIDGE, NEW JERSEY, ASSIGNOR TO THE COMFO ELECTRIC IRON COMPANY, OF GLEN RIDGE, NEW JERSEY, A CORPORATION OF NEW JERSEY.

ELECTRIC FLATIRON.

Application filed October 21, 1922. Serial No. 596,067.

To all whom it may concern:

Be it known that I, WILLIAM T. HOOFNAGLE, a citizen of the United States, residing at Glen Ridge, in the county of Essex 5 and State of New Jersey, have invented certain new and useful Improvements in Electric Flatirons, of which the following is a specification.

This invention relates to improvements 10 in electrically heated flat irons and more particularly to means for preventing the iron from becoming dangerously overheated if the current is left on when the iron is not in use, and also to the structure of 15 the top of the iron whereby the heat is conserved and the efficiency of the iron increased and the hand of the operator is protected from the heat of the iron.

In carrying out the invention, I provide 20 a top or cover for the iron which is made entirely of heat insulating material and the handle is secured to this top. The top confines the heat to the base, increasing the efficiency of the iron and protecting the 25 operator's hand from the heat of the iron. Within an opening in the top is arranged a fuse plug having clamping members at its lower end adapted to retain a fuse within the space above the base which is enclosed by 30 the top. This fuse forms part of the electric circuit through the heating element and when the iron becomes excessively hot, the fuse melts and interrupts the circuit through the heating element. Within the 35 plug and in series with the fuse and heating element is a filament which is visible through the top of the plug and remains luminous while the current is on. By observing this filament the operator can tell 40 at a glance whether the current is on or off and this lessens the danger of the current being left on when the iron is not in use. If the operator fails to note that the current is turned on when the iron is set aside 45 and does not disconnect the iron from the supply circuit, the overheating of the iron will cause the fuse to melt and the circuit through the heating element will thereby be interrupted. The fuse plug is provided 50 with clamping members adapted to grip the fuse when the plug is screwed into a socket in the cover and is so constructed that no current can flow through the heating element of the iron unless a fuse is placed between the clamping members. The inven-

tion also includes certain structural features of the plug and associated parts which will be hereinafter pointed out.

In the accompanying drawing,

Fig. 1 is a longitudinal vertical section 60 through the iron on the line 1—1 of Fig. 2;

Fig. 2 is a top plan view of the iron, the electrical circuits being shown in dotted lines;

Fig. 3 is a vertical cross section through 65 the iron on the line 3—3 of Fig. 2;

Fig. 4 is a top plan view of the body portion of the fuse plug;

Fig. 5 is a similar view of the insulating ring which forms an extension of the socket 70 in the cover;

Fig. 6 is an edge view of the same;

Fig. 7 is a top plan view of the movable fuse-clamping member;

Fig. 8 is a plan view of one of the fuses 75 bent into shape for use; and,

Fig. 9 is a top plan view of the connecting plate with the shell of the socket attached.

Referring to the drawing, *a* represents the base of the iron, which is of the usual form, 80 having a heating element 1, indicated in dotted lines, embedded in electrical insulating material 2. The top or cover *b* of the iron is of molded heat insulating material, preferably an asbestos composition, relatively thick in its central portion and having a flange *b'* at its edge which engages the perimeter of the base and spaces the central portion of the body away from the base. The top has embedded therein internally 90 threaded sockets 3 and 4, adapted to receive machine screws 3^a and 4^a, respectively, which secure the handle to the top. As shown, the handle comprises a hand piece or grip 5, to the ends of which are attached 95 the ends of a metal strip 6, bent into the form of a bail and having a straight central portion 6^a through which the screws extend into the threaded bushings or sockets in the top. The top, being composed entirely of 100 a relatively thick body of heat insulating material, prevents upward conduction and radiation of the heat from the base, and as the metal bail or strap of the handle is secured to this insulating material the heat 105 cannot be conducted from the base through the bail to the core of the grip. Hence, the grip will remain relatively cool to the touch and the top will protect the operator's hand against radiant heat from the base. 110

The top is secured to the body by a centrally located screw 7 which extends through a downwardly extending boss 8 upon the body and into the base, the head of the screw being countersunk in the top, as shown in dotted lines in Figs. 1 and 2. For positioning the top with respect to the base, the top is provided with downward projections 9 and 10 at the front and rear ends thereof, respectively, which projections engage the outer wall of the recess 11 in the base, wherein the heating element is located.

At one side of the handle the top is formed with a depression 12, which constitutes a pocket for holding a supply of fuses 13, and to retain the fuses in place the pocket is provided with a cover plate 14, removably secured to the top by machine screws, 20 one of which is shown at 15.

A circular opening 16 extends through the body of the top at the side opposite the aforesaid pocket, and within this opening is arranged a threaded metal contact shell 17, 25 adapted to receive a similar contact shell 18 on the outer side of a fuse plug *c*. The body 19 of the plug is made of suitable insulating material, such as porcelain, and is hollow, and is provided with a transparent cover 20, as usual, the latter being held in place by a sheet metal ring 21, flanged about the rim or bead 22 of the body. The ring 21 is provided with alined notches 23 so that the plug can be turned with the 30 blade of a knife, if it sticks and cannot be turned by the fingers of the operator. The base of the body portion of the plug has an opening extending centrally through it, the lower part 24 of the opening being cylindrical and the upper part 24^a being squared or angular in cross section, and on the bottom of the body portion is an annular projection 25 which forms a stop for a purpose hereinafter described. On the bottom of 40 the body portion and surrounding said stop is a flat metal contact ring 26 which is electrically connected to a metal ring 27 in the bottom of the cavity in the socket by screws 28 which clamp both rings to the body. A filament support 29 is connected to the ring 27 and a similar support 30 is connected to the threaded contact shell 18 of the plug, and a filament 31 of non-oxidizable metal, such as platinum, is connected 45 between these supports beneath the transparent cover or window 20. Thus, the plate 26 is electrically connected through the filament to the side contact shell of the plug.

The ring 26 constitutes one member of a 50 fuse clamp, the other member comprising a disk 32, having a central shank or stem 32^a which extends upwardly through the cylindrical opening 24 in the body of the plug and into the squared opening 24^a, and has 55 secured to its upper end a squared head 32^b

which prevents the shank and disk from turning with respect to the body of the plug. The shank is movable lengthwise in the opening so that a fuse wire, indicated at 33, may be clamped between the disk and the ring 26. The disk has in its upper side an annular channel 32^c, for receiving the fuse metal if the fuse melts. The fuse electrically connects the clamping members 26 and 32 when the fuse is gripped between them. If the fuse is removed, the clamping members cannot come in contact with one another because of the downward projection 25 on the insulated body which forms a stop to prevent such engagement. The current which flows through the heating element of the iron and the filament also flows through the clamping members and the fuse, as hereinafter explained. It will be evident, therefore, that the iron cannot be used unless the plug is fused, as the stop 25 will prevent the clamping members from engaging one another and the electrical circuit will be open between said members. The distance which the stop 25 projects below the 90 clamping ring 26 is less than the diameter of the fuse so that the stop will not interfere with the clamping of the fuse.

When the plug is in position, the movable clamping member rests upon a sheet metal contact piece *d*, which latter rests upon the insulating material 2 in which the heating element is embedded. This contact piece, as shown, is preferably in the form of a pan having its central portion pressed upwardly as shown at 34, and adapted to be engaged by the central portion of the disk 32 and having its marginal portion 34^a flaring outwardly and upwardly in order that it may be centered beneath the plug and 105 kept in position by a ring of insulating material 35 which is alined with the opening 16 in the top of the iron. The contact piece *d* has secured to its edge a metal strip 34^b which connects the contact piece with a terminal 36, which is embedded in the insulating material 2. One end of the heating wire or element 1 is connected to said terminal, as indicated in dotted lines in Fig. 2.

A plate 17^a, to which the contact shell 17 is welded, is secured to the underside of the top *b* by a bolt 37 which extends through an opening in the top and is provided with a nut 37^a for clamping the plate against the underside of the top.

Screws 38, passing through ears 35^a in the insulating ring 35, connect the ring to the top, and this ring, which forms an extension of the socket opening 16 through the top, extends downward around the contact plate 34 and below the edge of the plate. In assembling the parts of the iron, the contact plate 34 is connected by its attached strip 34^b to the binding post 36 and set in its approximate position on the insulat- 130

ing material 2. When the top is placed upon the iron, the tubular member 35 is placed over the contact piece 34 and when the top is adjusted to its position on the base, the contact piece 34 will be centered at the bottom of the opening 16 in which the fuse plug fits.

The usual terminals by which the iron is connected to the electric supply circuit, 10 through flexible conductors, are indicated at 40 and 41. These extend through the top or cover *b*, as shown and are secured directly thereto, the cover forming an insulating support for the terminals. The terminal 40 15 is connected by a flexible conductor 42 to a binding post 43, which is embedded in the insulating material 2 in the base of the iron, and from this terminal the heating wire or coil 1 extends toward the front of the iron 20 and then back to the terminal 36, as shown in dotted lines in Fig. 2. This circuit then proceeds through connection 34^b to the stationary contact *d*, thence through clamping member 32 to the fuse 33 and to the clamping 25 ring 26, thence through screws 28 to the ring 27 in the plug, thence through filament support 29, filament 31 and filament support 30 to the contact shell 18 on the plug, thence through the outer shell 17 and 30 its supporting plate 17^a to a metal strip 44 which connects said plate to the supply terminal 41. It will be evident from this description that when the iron is connected to the supply circuit, the current will flow 35 through the heating element, the fuse and the filament in series.

The fuses in the storage pocket are straight; but when a fuse is to be used it is bent into a more or less semi-circular form, 40 as shown in Fig. 8, and placed between the clamping members of the plug.

It will be understood from the foregoing that when the iron is to be used, the plug will be inserted in the socket, with a fuse 45 between the clamping members. As the plug is turned in the socket, the clamping member 32 engages the stationary contact *d* and the further turning of the plug causes the clamping members to grip the 50 fuse. If, now, the current is turned on, the heating element will cause the base of the iron to become heated and the filament 31 will become luminous and serve as a signal to the operator that the current is 55 flowing through the heating element. In the active use of the iron, the heat in the base is dissipated by the contact of the base with the fabrics which are being ironed; but if the operator should allow the iron to stand 60 for a time without use, the iron would become over-heated. This excessive heat in the cavity above the base wherein the fuse is located would cause the fuse to melt when a pre-determined temperature is reached.

65 If the fuse melts by reason of this excessive

heat, the fused metal will run into the channel or gutter 32^c in the clamping member 32. The melting of the fuse will open the circuit through the heating element by electrically dis-connecting the clamping members. The fuses are proportioned so that they will melt before the base of the iron reaches a high enough temperature to cause damage to wood or fabrics.

The main purpose of the filament is to 75 enable the operator to see whether the current is on or off when the iron is set aside. If the filament glows when the iron is set aside, of course, the operator will be reminded to disconnect the iron from the 80 supply circuit. If the operator fails to do this, then the fuse will melt before the iron reaches a dangerous heat, as above described.

It will be evident that the operator can 85 not use the iron without having it fused since the circuit through the heating element cannot be completed through the clamping members if the fuse is absent, by reason of the insulating projection 25 on 90 the socket which prevents said members from contacting in the absence of the fuse.

The insulating ring 35 serves as a guard to prevent molten fuse metal from becoming 95 scattered over the heating element.

What I claim is:

1. In an electric flat iron, a base having a heating element and a contact member, a cover having a socket provided with an internal contact, supply terminals on 100 the cover, one of which is connected through the heating element to the contact member of the base and the other of which is connected to said contact in the socket, and a fuse plug having a contact adapted to 105 engage the contact in the socket and having a metal clamp at its base adapted to grip a fuse, one member of said clamp being adapted to bear against the contact member on the base of the iron when the plug 110 is in the socket.

2. In an electric flat iron, a base having a heating element and a contact member, a cover having a socket provided with an internal contact and a fuse plug having 115 a side contact adapted to engage the contact in the socket and having a metal clamp at its base adapted to grip a fuse, said clamp comprising a member fixed to the end of the plug and a member movable with respect to said fixed member and adapted to bear against the contact member on the base of the iron when the plug 120 is in the socket.

3. The combination with an electric flat iron having a base provided with a heating element and a contact connected thereto and having a cover provided with a socket, of a fuse plug adapted to fit into said socket, 125 said plug comprising a body of insulating 130

- material having an opening in its base, a metal disk having a stem movable longitudinally in said opening, and a metal ring on the body opposed to said disk, said disk 5 adapted to engage the contact on the base of the iron when the plug is in the socket.
4. The combination with an electric flat iron having a base provided with a heating element and a contact connected thereto 10 and having a cover provided with a socket, of a fuse plug adapted to fit into said socket, said plug comprising a body of insulating material having an opening in its base, a metal disk having a stem movable longitudinally in said opening, said disk having an 15 annular channel in the side next the plug, and a metal ring on the body opposed to said disk, said disk adapted to engage the contact on the base of the iron when the plug 20 is in the socket.
5. The combination with an electric flat iron having a base provided with a heating element and a contact connected thereto and having a cover provided with a socket, of 25 a fuse plug adapted to fit into said socket, said plug comprising a body of insulating material having metal clamping members at its base, said body having a projection adapted to prevent the co-engagement of 30 said clamping members, one of said clamping members being adapted to engage the contact on the base of the iron when the plug is in the socket.
6. In an electric flat iron, a base having a heating element embedded in insulating material and a circular contact member connected to said element and resting on said material, a cover having a socket and a ring of insulating material registering with said socket and surrounding said contact member, and a plug adapted to fit in said socket and having a fuse clamp at its base adapted to engage said contact member. 35
7. In an electric flat iron, a base having a heating element and a cover composed of heat insulating material extending over the base and enclosing the heating element, a handle secured to said cover, and a fuse plug extending through the cover and engaging a metal part on the base. 40
8. In an electric flat iron, a base having a heating element, a cover composed of heat insulating material extending over the base and enclosing the heating element, supply circuit terminals secured directly to said cover, and a fuse plug extending through the cover and engaging a metal part on the base. 45

In testimony whereof I hereunto affix my signature.

WILLIAM T. HOOFNAGLE.
